UNITED STATES PATENT OFFICE.

ODILON BRISBOIS, OF CHICAGO, ILLINOIS, ASSIGNOR OF FIFTY-ONE ONE-HUNDREDTHIS
TO JOHN H. WARE, OF CHICAGO, ILLINOIS.

TYPE-WRITER CARRIAGE-RETURN DEVICE.

1,140,333.

Specification of Letters Patent. Patented May 18, 1915.

Application filed October 8, 1914. Serial No. 364,816.

To all whom it may concern:

Be it known that I, ODILON BRISBOIS, a citizen of the United States, and a resident of Chicago, in the county of Cook and State 5 of Illinois, have invented certain new and useful Improvements in Type-Writer Carriage-Return Devices, of which the following is a specification, regard being had to the drawings accompanying and forming a 10 part hereof.

This invention relates to means to return the carriage of a type writer from its position at the end of a line to a position at the beginning of the next line.

15 The object of the invention is to obtain a device which can be set to return the type writer carriage automatically, from the end of a line of a determined length to the beginning of the next line; to obtain a device 20 which will permit the operator to depress a key when the end of a line of less than said determined length is reached, and thereupon the device will return the type writer carriage to the beginning of the next line; 25 and to obtain a device which can be attached to a type writer already in use, without necessitating the return of said type writer to a factory.

A further object is to obtain a device 30 which may be actuated by the electric current ordinarily used for lighting offices, houses, halls and the like.

To those skilled in the operation of type writers it is known that the sheet of paper 35 on which type characters are to be made is usually mounted on a roller carried by a carriage, and that said carriage travels the length of a line of said characters, and is then returned to the beginning of the next 40 line by the operator; and it is also known that when a type writer is continuously operated for a number of hours the energy required to return the carriage becomes a severe strain to many persons. It may, 45 therefore, be said that the ultimate purpose of this invention is to relieve the operator of the labor entailed in returning a type writer carriage to the beginning of a line.

I have illustrated a device embodying 50 this invention in the drawings hereinbefore referred to in which—

Figure 1 is a rear elevation of a type writer frame, and of a device embodying this invention secured in place thereon. 55 Fig. 2 is a diagram of the electric switches,

circuits, and motor of the device. Fig. 3 is a side elevation of a type writer frame, with the device in position thereon; and Fig. 4 is a top plan view of the device. Fig. 5 is a side elevation of the device, 60 showing the opposite side to that which is illustrated in Fig. 3. Fig. 6 is a perspective of an adjustable stop forming an element of the device. Fig. 7 is a perspective of a rock shaft, forming an element of the shaft 65 of a motor, a reel and a ribbon thereon, which form elements of the device.

A reference character applied to designate a given part indicates said part 70 throughout the several figures of the drawings wherever the same appears.

X is a type writer frame; and Y is a shelf at the rear or back of said frame.

Z, (Fig. 3) is a portion of the type writer 75 carriage return mechanism ordinarily used on well known makes of type writers; and comprises a shaft which has a slight rocking movement in suitable bearings.

Z¹ is a small portion of a type writer 80 carriage.

A is the base of the device embodying this invention.

a is a motor secured on base A.

B is the shaft of the armature of motor 85 a, (Figs. 1, 3 and 8).

C is a casing which is secured to the housing of motor a. Casing C is non-rotatable and comprises parallel plates, or disks, which are connected by screws or bolts C¹ 90 and the rollers C², which are rotatably mounted on said screws or bolts.

D, Figs. 1 and 3, is a split journal bearing, which is provided with base d fitting on part Z¹ of the type writer carriage, and 95 secured to said part by screw d¹.

d² is a screw, by means of which the split bearing D is adjusted to shaft E. The end of the horizontally disposed part of shaft E is screw threaded, as at e, to fit into a 100 correspondingly screw threaded hole in the end of part Z of the ordinary type writer carriage return mechanism. Shaft E is provided with bend e¹, so that the part E¹ of said shaft is substantially vertical.

Part Z is adapted to rock slightly in suitable bearings and a rocking motion is imparted thereto, by this device, by the swinging of part E¹ of shaft E; and said rocking movement turns the paper carriage 110

- roller for the next line to be type written. This turning of the paper roller is effected by mechanism intervened between said part Z and the roller; said intervening mechanism varying on different type writers, and forming no part of this invention.
- F, F¹, are standards on base A. Standards F, F¹, are illustrated as being the vertical members of a U shaped piece which is formed up from ductile metal and secured to said base by screws f. Said vertical members are provided with needle bearings for a rock shaft (H). Member F is provided with lugs or ears f¹, on which key G, G¹ is pivoted by means of pivotal pin g¹. Part G¹ of key G, G¹ is secured to part G by means of screws or bolts g. The rock shaft H is mounted on bearings h, h¹.
- I, I¹, I², I³, are arms on rock shaft H.
- J is a spring which is attached at one end to arm I³, and at the other end to adjustable post j. When arm I is in the position which is illustrated by full lines in Fig. 1, spring J tends to hold it in said position and when said rock shaft is in the position in which arm I is indicated by broken lines said spring J yieldingly holds it in said last named position. This action of spring J is because the end of said spring which is attached to arm I³ is above the center of pivots h, h¹, when arm I is in the position illustrated by full lines, and said end of said spring is below said pivots when said arm is in the position indicated by broken lines.
- In the movement of arm I from one to the other of the above described positions said end of spring J moves above, (or below) the center of said pivots before the completion of said movement of said arm; and hence, the end of said movement, (in both directions), is effected by said spring, and is correspondingly rapid.
- The end of part G¹ of key G, G¹, is underneath arm I², so that depression of the end of part G and raising of the end of part G¹, forces the end of arm I² upward, rocking shaft H on pivots h, h¹, from the position illustrated by the full lines of arm I to the position with arm I in the position indicated by broken lines. As shaft H is rocked to move arm I from the position illustrated by full lines in said Fig. 1 to the position indicated by broken lines, arm I¹ is moved down, to quickly close the switch K. Switch K consists of spring blades k, k¹, and k², and in the downward movement of arm I² blades k and k¹ are first brought into electrical contact, and immediately thereafter blades k¹ and k² are brought into electrical contact. When the shaft H is rocked back to its initial position arm I¹ is raised, and the electrical contact of blades k¹, k² is first broken; and immediately thereafter the electrical contact of blades k, k¹, is broken, (by the resiliency of said blades).

K¹ is a resistance coil.

K², (Fig. 2) represents the coils of the motor a.

L, L¹, are the binding posts of the motor, to which the wires of the supply circuit are attachable.

M¹, M, are electric conductors forming elements of the motor, (see Fig. 2).

When blades k, k¹, of switch K are in electrical contact a closed circuit is obtained in which the binding posts L, L¹, conductor M, resistance coil K¹, the coils (K²) of the motor a, and conductor M are elements, and when blades k¹, k², are in electrical contact a closed circuit is obtained in which said binding posts, conductors M, M¹ and the coils of the motor are elements with resistance coil K¹ shunted. By thus first placing resistance coil K¹ in the circuit with the motor, sparking at electric terminals n, n¹ and n², of said switch K is obviated; in making or closing the circuit; and in breaking said circuit the replacing of said resistance therein at the time the electrical contact of blades k, k¹, is broken, obviates sparking at said time.

O, O¹, are grooved rollers rotatably mounted on standard F; and P is a hollow bar, one end of which is attached to the end of part E¹ of shaft E, (by means of insulating fiber e, rod e¹, and pivot e²), and mounted between said rollers, to move longitudinally to the right and left as the carriage of the type writer moves or is moved on frame X.

p, p, are teeth on bar P, corresponding with the teeth of the type writer escapement, so that, as a tooth of said escapement permits a determined movement of the type writer carriage said movement is measured by one of said teeth on said bar P.

Q, Q, are, respectively, posts mounted on bar P. Post Q, illustrated in Figs. 1 and 2 as at the right hand end of bar P, determines the commencement of the line to be type written; and post Q, at the left hand end of said bar P, determines the end of the longest line to be type written, when this device is attached to the type writer. To permit the commencement and the ending of said lines to be varied said posts Q, Q, are made adjustable on bar P, and are constructed as follows:—Body Q¹ is slideable in bar P, and is provided at one end with teeth q, which are engageable with the teeth p; and spring q¹ is attached to body q to yieldingly hold said body with said teeth advanced to engagement with teeth p. Posts Q, Q are mounted on a body Q¹, respectively. To move the posts from a given position on bar P to a different position the post is forced longitudinally into bar P to release the teeth q from engagement with teeth p, and is then moved along the bar to any desired position. On releasing the post

130

it is forced forward by spring q^1 , into position with the teeth q again in engagement with teeth p .

The hereinbefore described arm I is in the path of movement of the posts Q, Q. With said arm in the position illustrated by full lines in Fig. 1 the post Q which is illustrated as to the left of said arm I, in Figs. 1 and 2, is forced against it when the end of the line is nearly reached, and said arm is moved toward the position indicated by the broken lines in said figure. On the return of the carriage, by the about to be described mechanism, the post Q, which is illustrated in said Figs. 1 and 2 as to the right of said arm I, is brought against said arm when the commencement of the next line is about to be reached, and said arm is returned to its initial position. The movement and operation of arm I is the same when said post Q, which is to the left thereof, as illustrated in Figs. 1 and 2, is forced against it as when the key G, G^1 is actuated, as hereinbefore described.

The mechanism which moves bar P from the right to the left, as viewed in Fig. 1, consists of the following elements: r is insulating material and R is a post secured, by means of said insulating material, to one end of bar P. S is a spring, secured at one end to post R and at the other end to ribbon T. The other end of ribbon T is attached to shaft B of motor a. The ribbon T is made of slightly resilient material. The purpose of making said ribbon of resilient material is to prevent it from lying tightly coiled around said shaft B; and the action of said ribbon is such that when the motor is started by the closing of the switch K but little resistance is offered to the rotation of the shaft B thereof; and said motor is permitted to get a start. The movement of the shaft winds the ribbon tightly thereto, and the spring S is lengthened by the strain thereon required to overcome the resistance of bar P and the mechanisms actuated thereby. The initial movement of said bar P, (to the left) rocks shaft E and turns the paper roller of the type writer to the determined point for a new line of type writing, and further movement of said bar moves the mechanisms attached to said shaft to the left.

When the movement of bar P to the left forces pin Q against arm I the shaft H is rocked to break, as hereinbefore described, the circuits of motor a; and thereupon the inertia of the armature of said motor again elongates spring S. The retraction of said spring turns said armature and shaft B backward, and the resiliency of the ribbon T produces still further backward rotation of said shaft B. The movement of said bar P to the right turns said shaft B backward and when the circuits of the motor a are again closed initial rotation of said shaft

B is permitted, to wind the ribbon T tightly thereto, as hereinbefore recited, before any considerable work is required of said motor.

I claim;

1. The combination of a switch, a resistance coil, a motor, and conductors, all arranged to obtain circuits, in one of which circuits said motor is a member and in the other of which said motor and resistance coil are elements, a shaft to control said switch, and thereby successively open and close said circuits, means to yieldingly hold said shaft in an operated position, a longitudinally movable bar, a flexible connection between said bar and said motor, and a connection between said bar and a type writer carriage, means on said bar to automatically operate said shaft when said bar is moved in one direction, and means on said bar to automatically operate said shaft when said bar is moved in the opposite direction, and means to manually operate said shaft.

2. The combination of a switch, a resistance coil, a motor, and conductors, all arranged to obtain an electric circuit in which said motor is an element and a circuit in which said resistance coil and motor are elements, a shaft to control said switch, means to yieldingly hold said shaft in an operated position, a longitudinally movable bar, a connection between said bar and said motor to move said bar in one direction by said motor, and a connection between said bar and the carriage of a type writer to move said bar in the opposite direction by the movement of said carriage, means on said bar to automatically move said shaft to successively open said circuits when said bar is moved longitudinally by said motor, and means on said bar to automatically move said shaft to successively close said circuits when said bar is moved by said carriage.

3. The combination of a switch, a resistance coil, conductors arranged to obtain a circuit in which said resistance coil and said motor are elements, and a circuit in which said motor is an element, a longitudinally movable bar, a spring attached to one end of said bar and a connection between said spring and said motor, a connection between said bar and a type writer carriage, adjustable abutments on said bar, a shaft, arms to said shaft, one of said arms in the path of movement of said abutments, and an additional one of said arms adapted to close said switch, means to yieldingly hold said shaft in an operated position, a manually operated key, and an additional one of said arms in the path of movement of said key.

4. The combination of a switch, a motor, a resistance coil, conductors arranged to obtain an electric circuit in which said resistance coil and said motor are elements, and a circuit in which said motor is an element,

a longitudinally movable bar, a connection between said bar and said motor, a type-writer carriage, a connection between said bar and said type writer carriage, adjustable 5 abutments on said bar, a shaft, arms to said shaft, one of said arms in the path of movement of said abutments, and an additional one of said arms adapted to close said switch, and means to yieldingly hold said 10 shaft in an operated position.

5. The combination of a rock shaft, means to yieldingly hold said shaft in a given position, a switch, means to move said rock shaft from said given position, to close said 15 switch, an electric circuit in which said switch and an electric motor are members, and a connection between said motor and a type writer carriage, to move said carriage when said motor is energized, and means to 20 automatically return said rock shaft to its initial position, when said motor has returned said carriage to its initial position.

6. The combination of a rock shaft, means to yieldingly hold said rock shaft in a de-

termined position, a switch, a resistance coil, 25 a motor, a connection between said motor and a type writer carriage, a circuit in which said switch, resistance coil and motor are members, and a circuit in which said switch and motor are members, means comprising 30 adjustable posts mounted on said typewriter carriage to move said rock shaft from its determined position to close said circuits in succession by the closing of said switch, means to automatically return said rock 35 shaft to its initial position to break said circuits in succession, the one of said circuits of which said switch and motor are members being broken before the circuit is broken of which said switch, resistance coil and motor are members. 40

Signed at Chicago, Illinois, this 19th day of September, 1914.

ODILON BRISBOIS.

In the presence of—

CHARLES TURNER BROWN,
CHARLES B. HEBRON.
